UNITED STATES PATENT OFFICE.

THOMAS OSBORNE HOLLAND, OF PHILADELPHIA, PENNSYLVANIA.

TOOTH-POWDER RECEPTACLE.

SPECIFICATION forming part of Letters Patent No. 611,410, dated September 27, 1898.

Application filed May 5, 1897. Serial No. 635,243. (No model.)

To all whom it may concern:

Be it known that I, THOMAS OSBORNE HOLLAND, a citizen of the United States, residing at Philadelphia, in the county of Philadelphia and State of Pennsylvania, have invented certain new and useful Improvements in Tooth-Powder Receptacles; and I do hereby declare the following to be a full, clear, and exact description of the invention, such as will enable others skilled in the art to which it appertains to make and use the same.

This invention relates to tooth-powder receptacles.

The object is to produce a receptacle for containing tooth-powder, in the use of which only the requisite amount of powder will be deposited upon the brush, thereby saving the powder and preventing the same from falling upon the apparel, as frequently occurs by the use of receptacles in common use; furthermore, to provide a receptacle in which the contained powder will be shielded from contact with moisture, which causes it to clog, rendering its removal from the receptacle somewhat difficult; furthermore, to provide a receptacle which in use will not become foul and ill-smelling; furthermore, to provide a receptacle which may be readily filled when empty, and, finally, to provide a receptacle which will be neat and attractive in appearance, efficient and durable in use, and cheap to manufacture.

The powder-receptacle characterized by my invention is adapted more particularly for the use of traveling salesmen where compactness and readiness in use is particularly desirable.

In the ordinary powder-receptacles in common use the brush has to be dipped into the powder, and the result is that more powder than is necessary is frequently taken up, thereby causing waste, and the drip from the tooth-brush also causes the powder to ball up and become clogged, thereby rendering its use difficult. To obviate these objections, I provide a powder-receptacle which in use will deposit only the necessary amount of powder upon the brush and in which the deposit is accomplished in such manner that any drip from the tooth-brush will not enter the receptacle, thereby obviating clogging or balling of the tooth-powder.

As a matter of further and specific improvement I provide at the discharge-mouth

of the receptacle a resilient gasket, of a non-absorbent inodorous material, having an opening of a size of the bristle portion of the brush and against which the bristles will bear in use, and back of this gasket or mouthpiece I provide a foraminous plate or partition through which the powder is sifted. In order to effect an air-tight closure, I provide the lid with a packing of an inodorous waterproof yielding material which when the lid is closed will fit within the open space of the gasket, and thereby prevent escape of the powder. To provide for the ready filling of the receptacle, I employ a bottom having a packing of inodorous waterproof material which will fit within the receptacle and close the same. Both the bottom and top may be held in place by frictional contact with the walls of the receptacle; but as a matter of specific improvement I prefer to hinge both the bottom and top of the receptacle and provide suitable spring-catches for holding the parts closed. The body of the receptacle may be made of any suitable material, preferably of alumina or nickel, and of any shape in cross-section, preferably rectangular, with the corners rounded, so as to obviate the presentation of sharp projections.

Further and more specific details of construction will be hereinafter fully described.

In the accompanying drawings, forming part of this specification, and in which like letters of reference indicate corresponding parts, I have illustrated a form of embodiment of my invention, although it is to be understood that other forms of embodiment thereof may be employed without departing from the spirit of the same, and in these drawings—

Figure 1 is a view in perspective displaying the receptacle with the lid open and showing the gasket at the mouth of the receptacle, the sifter, and the packing on the lid for closing the mouth of the receptacle. Fig. 2 is a view in longitudinal vertical section, showing more clearly the disposition of the foraminous partition, the gasket, the bottom, and the lid, the lid and bottom being closed. Fig. 3 is a view in longitudinal section displaying a modification of gasket, consisting of a sheet of metal stamped or otherwise formed to appropriate shape and secured to the upper inner edges of the receptacle and bearing upon or secured to the

foraminous partition. Fig. 4 is a sectional detail view displaying a modification in the shape or form of the foraminous partition, the same being curved upward, so as to guide the powder toward the center of the partition to prevent it being banked up at the sides of the receptacle; and Fig. 5 is a sectional detail view showing a slide which may be used to cover the foraminous partition when in one position and to clear the openings of the same when moved to another position.

Referring to the drawings, A designates the receptacle, which may be made of any suitable material and of any shape in cross-section, A² the lid, and A³ the bottom. Secured within the receptacle, near its top, is a foraminous partition a, constituting a sifter, and secured to and resting upon this partition and extending flush, or substantially so, with the upper edge of the receptacle and extending to the perforations of the partition is a gasket or cushion a², made of any suitable inodorous waterproof substance, preferably of cork, and provided with an opening into which the bristles of the brush can be placed. The walls of this cushion are rounded or convexed, so that when a brush is pressed against them the bristles at the ends and sides will be compressed or forced inward, thereby preventing escape of the powder, contact of the bristles with the partition being prevented by the rounded walls, thereby shielding the partition from moisture and consequent rust. The lid A² may be of the ordinary kind that is held in place by frictional contact with the sides and ends of the receptacle; but as a matter of specific improvement I prefer to hinge the lid to the receptacle and provide the lid with an ordinary spring-catch a³ for engaging a projection a⁴ on the receptacle, or any other form of fastening device may be employed. Secured upon this lid is a packing a⁵, of any inodorous waterproof material, preferably of cork, the sides and ends of which are beveled or concaved to conform to the walls of the gasket, so that when the lid is closed these beveled portions will engage with the rounded or convexed walls of the opening in the gasket, and thereby effect a powder-tight closure.

The bottom A³ may, if preferred, be held in position by frictional contact with the sides and ends of the receptacle; but I prefer in this instance to hinge the bottom to the receptacle and to provide a spring-catch similar to that used in connection with the lid to hold the bottom closed. This bottom is also provided with a packing a⁶, preferably of cork, which will effectively close the bottom of the receptacle and prevent escape of its contents.

In use the lid is opened and the bristles of the brush are pressed or held against the walls of the gasket. The receptacle is then turned to allow the powder to fall upon the brush,

and by lightly tapping on the bottom of the receptacle or shaking the same the desired quantity of powder may be sifted onto the brush, after which the lid is closed. When the receptacle is emptied, the bottom A³ is opened and powder filled to the receptacle in any manner.

In Fig. 3 I have shown the receptacle as provided with a cushion or gasket made of metal, the same being stamped to the appropriate shape with beveled or curved sides and secured in the receptacle at its upper inner edges and having its bottom either resting upon or secured to the foraminous partition. This form of cushion will be found efficient in use and by reason of its being made of nickel or being nickel-plated or made of alumina will be inodorous, and therefore thoroughly clean.

In Fig. 4 I have shown the foraminous partition as curved upward toward the mouth of the receptacle for the purpose of preventing powder from banking up at the corners where the partition is secured to the sides and end of the receptacle and also to guide the powder toward the center of the partition, where it escapes upon the brush.

In Fig. 5 I have shown still another modification in which, in addition to the ordinary foraminous partition a⁷, I employ a slide, also provided with openings, the slide when pushed in in the position shown in Fig. 5 closing the openings in the partition and when pulled out the necessary distance will open the same. By this arrangement the lid may be dispensed with; but it is preferred to employ the lid.

Having thus fully described my invention, what I claim as new, and desire to secure by Letters Patent of the United States, is—

A tooth-powder receptacle comprising a body portion, a foraminous partition secured near the top thereof, a cushion or gasket resting upon the partition and having its upper surface flush with the edges of the mouth of the receptacle, the sides and ends of the gasket being rounded from the said mouth downward to the partition, and operating, in use, to compress the hairs of the brush to prevent waste of the powder, a lid hinged to the receptacle, and having a packing formed to fit upon the gasket, when the lid is closed, to prevent escape of the contents of the receptacle, a hinged bottom also having a gasket to effect a dustproof closure at that point, and means for holding the top and bottom closed, the construction being such that a brush may be fitted into the opening and rest against the said partition, whereby both the partition and the box are kept free from wet powder, substantially as described.

In testimony whereof I affix my signature in presence of two witnesses.

THOMAS OSBORNE HOLLAND.
